UNITED STATES PATENT OFFICE.

LOUIS ILLMER, JR., AND EDWARD J. KUNZE, OF NEW YORK, N. Y., ASSIGNEES, BY DIRECT AND MESNE ASSIGNMENTS, TO ILLMER GAS ENGINE COMPANY, A CORPORATION OF DELAWARE.

INTERNAL-COMBUSTION ENGINE.

1,054,204.

Specification of Letters Patent.

Patented Feb. 25, 1913.

Original application filed February 16, 1903, Serial No. 143,598. Divided and this application filed February 4, 1904, Serial No. 191,988. Renewed April 12, 1912. Serial No. 690,314.

To all whom it may concern:

Be it known that we, LOUIS ILLMER, Jr., and EDWARD J. KUNZE, citizens of the United States, and both residents of the city 5 of New York, borough of the Bronx, in the county and State of New York, have invented a new and Improved Internal-Combustion Engine, of which the following is a full, clear, and exact description.

110 Our invention relates to certain improvements in the valve and cylinder head construction of internal combustion engine power cylinders, and is especially, although not necessarily, applicable to those of the 15 double acting two stroke cycle type, all of which improvements will be fully set forth hereinafter and particularly pointed out in the claims.

The present application is a division and 20 continuation of the application for patent on internal combustion engines, filed by us Feb. 16, 1903, Serial No. 143,598.

Reference is had to the accompanying drawings for a specific disclosure of our invention, in which drawings:—

Figure 1 is a side elevation of the engine. Fig. 2 is a vertical longitudinal section thereof. Fig. 3 is a diagrammatic view showing the mixing and the fluid pressure 30 central-valves, the latter controlling the fluid pressure for operating the inlet valves. Fig. 4 is an enlarged horizontal section of one end of the power cylinder, illustrating the novel head and valve construction. Fig. 35 5 is an enlarged section of the inlet valve, and valve housing ports.

As best shown in Figs. 2 and 4, the reference numeral 10 represents the power cylinder which is tied to the frame parts of 40 the engine and sustained by base parts extending to the floor line. The power cylinder bore is suitably water jacketed by the annular wall 23 which provides a surrounding space for the circulation of the 45 cooling fluid. As shown in the drawings, the jacket wall 23 is cast separate from the cylinder body but if preferred may be formed integral therewith. The cylinder 10 is further provided with exhaust ports 50 12 located intermediate the ends of the bore

and adapted to be overrun by the piston 20 in the customary manner of engines of the two stroke cycle type.

Each end of the power cylinder 10 carries an attached cylinder head and as best 55 shown in Fig. 4 each head consists of a gyrate or annular head wall 17 positioned in the longitudinal axis of the cylinder and encircling the piston rod. The head wall illustrated, is substantially in the form of a 60 hollow frustum of a cone having a central opening in its contracted end constituting the inlet port into the power cylinder and flaring outward to the bore diameter of the cylinder. The essential feature of the head 65 wall 17 is its gyrate formation encircling the piston rod and the admitting of the working charge in alignment with the longitudinal axis of the power cylinder.

The large diameter of the head wall 17 70 is provided with an inner flange 17^a by which the head may be bolted to and lightly fitted against the end of the power cylinder. The contracted end of the head wall is likewise provided with a flange 17^b to which 75 the valve housing 18 is removably attached.

Fig. 2 represents the piston 20 located on its head end dead center position and shows the formation of the combustion chamber around the piston rod and within the gyrate 80 head wall 17. By thus causing the explosion to take place within the cylinder head parts, the cylinder bore is relieved to a large extent of the stress resulting from the high temperature and pressure of explosion. The head wall 17 surrounding the explosion chamber is particularly adapted to 85 withstand the rapidly repeated strains resulting from such explosions of the working charge.

The drawing shows the head wall 17 as a 90 separate casting surrounded by an annular jacket wall 21, the latter also separately cast and spaced from the former so as to permit water circulation for cooling the 95 head wall 17. The jacket casting 21 is also shown flanged at its ends, one such flange 21^b bears snugly against the end of the power cylinder, while the other flange 21^a is rigidly tied to the cylindric part or housing 100

29 of the engine frame 31. A relatively flexible dished plate 22 or its equivalent in a yielding water tight seal, extends between the outer flange 17^b of the head wall and the flange 21^a of the head jacket. This construction permits of independent expansive movement of the head wall with respect to its jacket wall 21 whereby to relieve the high internal expansion or contraction stresses that would otherwise be set up between these parts.

10 The simple gyrate head wall 17 is exceedingly strong as against explosive pressure and is not given to warp under the influence 15 of high temperature. Furthermore the head parts can readily be rid of their casting strains and the working stresses in these parts estimated with a considerable degree of certainty, thus insuring lightness of construction and effective cooling of the head parts.

15 It will also be apparent that the cylinder head parts can be removed from either end of the cylinder through the frame housing 20 parts without disturbing the alinement of the engine.

25 The valve housing 18 consists of an outer tubular wall which is provided at its attached end with a flange 18^a whereby it is bolted or otherwise fastened to the head wall 17. The free end of the said outer wall of the housing is turned inwardly and is joined to an inner tubular wall 44 through which the piston rod 19 passes. As is best 30 shown in Fig. 5, the inner wall is concentrically mounted within and spaced from the outer wall to form an annular feed passage 37 through the valve housing which leads from the lateral opening 37^a to the 35 inlet port 39 of the power cylinder 10. A suitable packing 36 is provided between the valve housing parts 18 and the piston rod 19, which rod passes centrally through the valve housing parts.

40 45 The elongated shape of the annular passage 37 allows the air and gas to turn and assume longitudinal movement with respect to the cylinder axis before reaching the inlet valve, thus tending to discharge equally over 50 all parts of the valve opening and at the same time not requiring the direction of flow of the gases to be turned after discharging from the inlet valve 41.

55 Extending laterally from the valve housing 18 is a conduit or duct 48, which passes through an opening in the cylindric housing 29 of the engine frame 31. One end of the conduit communicates with the valve casing 55, the purpose of which casing will 60 hereinafter appear. The other end of the duct 48 discharges into the lateral housing opening 37^a and connects with the annular feed passage 37 surrounding the piston rod.

65 The opening of the passage 37 into the power cylinder is commanded by the inlet

valve disk or head part 41, which valve is also annular in shape and coacts with an annular valve seat part 38 and forms an extension of the valve housing parts 18. The seat part 38 is shown cast separate from the valve housing proper, but if preferred may be formed integral therewith.

70 To the inlet valve 41 is attached a tubular stem 42 which also encircles the piston rod, is supported by the valve housing parts and is slidably mounted therein. As is best 75 shown in Fig. 5, the valve 41 and its integral tubular stem 42 are held spaced from and out of contact with the piston rod 19 so as not to be directly affected by the piston rod 80 movements. The mounting of the valve within the valve housing parts 18, surrounding but held free from the piston rod, constitutes an important feature of the present invention. By this means the operation and 85 seating of the valve are not affected by lack of alinement such as may be due to wear in the supporting parts, sag or springing of the piston rod and the like.

90 As far as the present invention is concerned, the inlet valve may be operated by any fit gear mechanism. The drawings show the valve stem 42 fitted with an annular ring constituting a piston like member 43, suitably mounted in the valve housing parts and 95 adapted to bear compressed air or other fluid pressure. In order to seal against the explosion pressure, packing rings 45 are provided between the tubular valve stem and the valve housing parts. The passages 46 and 47 leading respectively to the sides of the piston member 43, are such that air pressure communicated through the passage 46 will close the valve while pressure communicated through the passage 47 will open the 100 valve. By this means the valve may be actuated by compressed air in both directions. By the use of suitable fluid pressure control devices the valves may be operated in synchronism with the piston movements. For 105 this purpose, air connections 61 and 63 (see 110 Figs. 1, 2, 3 and 5) lead outward from the passages 46 and 47 and communicate respectively with the air pipes 63 and 64, which in turn lead respectively from the chambers 65 and 66 of the timing valve casing 67. Intermediate the chambers 65 and 66, said casings 67 are each provided with a feed chamber 68 to which the compressed air supply pipes 70 lead. Each of these casings also has a chamber 69 which serves as an exhaust chamber. The casings further contain suitably ported valve bushings 71 communicating respectively with the chambers 65, 66, 68, and 69, which ports are controlled by the 120 piston valves 76. These valves are connected by means of the rod 78 and operate together.

125 As shown in Fig. 3, the right hand timing valve 76 connects the feed chamber 68 with 130

the chamber 66, causing compressed air to flow through the pipe 64 to open the right hand inlet valve. The said timing valve also connects the chambers 65 and 69 so as to exhaust the pressure from the pipe 63. While the right hand valve is in the described position, the left hand valve assumes the opposite position, to wit, connecting the chambers 68 and 65 so as to throw pressure 10 in to the pipe 63 and thereby closing the left hand inlet valve. The timing valve is reciprocated by the crank shaft eccentric 82 and thus causes air pressure to be alternately applied to and exhausted from the pipes 63 and 64, and consequently through the connections 61 and 62 and the passages 46 and 47, whereby the inlet valves will be alternately opened and closed in time with the charging period of the power cylinder.

20 Both the head end and the crank end valve and cylinder head parts are shown similarly constructed, the drawings illustrating the use of a tail rod for the piston 20 passing centrally through the head end 25 valve housing 18 and supported by the rear crosshead 24. The use of a tail rod is not, however, essential and if preferred the inner tubular wall of the head end housing may be plugged, and the tail rod dispensed with.

30 As stated, the conduit or duct 48 discharges into the annular passage 37 of the valve housing 18. The receiving end of each of said ducts communicates with separate casings 55, each of which contains a 35 control device for forming, measuring and letting forward alternate bodies of scavenging air and of explosive mixture into the power cylinder. Said casings are each provided with an air supply chamber 55^a and a 40 gas supply chamber 55^b controlled by the stratifying valve 60. The air and gas supplies are separately compressed by any fit means to a pressure sufficient to give mobility to these fluids, which initial compression 45 is preferably accomplished by the system of centralized pumping units as set forth in our co-pending application for patent, Serial No. 223,878 filed Sept. 9, 1904.

The arrangement of the casing parts is 50 such that the valve 60 may move to open the air supply only to the duct 48 or to open both the air and gas supply to said duct. These conditions take place alternately under the reciprocation of the valve 55 60. The air and gas supplies being under low pressure, results in sending from the casing 55, first a body of air and then a body of explosive mixture, which in this formation pass on into the power cylinder. 60 These operations are so timed that upon opening the exhaust port 12 and the inlet valve 41, the body of air at this instant lying in the passage 37 back of but quite up to the inlet valve, passes into the power 65 cylinder to constitute the scavenging air,

which in turn is followed by the mixture body which takes its place in the power cylinder as the working charge.

The central location of the annular inlet valve 41 with respect to the axis of the gyrate cylinder head walls 17 further serves an important purpose in spreading the working charge as it passes into the ends of the power cylinder 10. As the motive fluid discharges from the lateral ducts 48 and 75 passes into the valve housings 18, the confining walls of the elongated annular passages 37 cause the charge to turn and assume movement in the direction of the cylinder axis before reaching the annular inlet ports 39. As either inlet valve opens and 80 admits the working charge into the power cylinder, it acts as a baffle to divert the charge toward the surrounding gyrate cylinder head wall 17, whereby to permit active 85 eddying. Thus a considerable portion of the kinetic energy attained by the gases in flowing through the inlet valve opening, will be absorbed and the velocity of the incoming charge after it has passed the inlet, 90 will be rapidly reduced.

The bodies of scavenging air and of explosive mixture are necessarily charged into the power cylinder at a rather high velocity in order to complete this operation within 95 the short time allowed for the charging period when running at the usual engine speed. While open, the described inlet valve acts essentially as a baffle placed across the power cylinder axis. This action 100 prevents the scavenging air and explosive mixture bodies from rushing directly through the center of the power cylinder and tends to spread the incoming charge over the entire cylinder area, thereby maintaining and preserving to a considerable extent the described formation of successive bodies of scavenging air and of explosive mixture as they enter the power cylinder. 105

The central location and the annular construction of the inlet valve around the piston rod readily admit of exceptionally large feed opening into the power cylinder. This results in a relatively low velocity of flow through the valve and in a reduced tendency 110 of the incoming charge to rush toward the then open exhaust ports, and in tending to fill the power cylinder with explosive mixture whereby to increase its volumetric and power capacity.

We claim:—

1. In an internal combustion engine, the combination of a double acting power cylinder having an exhaust port intermediate its ends; a piston adapted to overrun and 115 time the exhaust port; a combustion chamber located at each end of the cylinder; an annular inlet port encircling the longitudinal cylinder axis respectively for each combustion chamber and opening directly there- 120

- 1 into; a motive fluid inlet valve respectively commanding each of said ports; means discharging alternate bodies of scavenging air and of explosive mixture to each inlet valve, 5 whereby said valves, when open, serve as baffles to maintain the said formation of the gases on their way into the power cylinder; and a gear mechanism for positively operating the valves.
- 10 2. In an internal combustion engine, the combination of a double acting power cylinder having an exhaust port intermediate its ends; a piston adapted to overrun and time the exhaust port; a piston rod; a combustion chamber located at each cylinder end; a motive fluid inlet port respectively for each combustion chamber and opening directly thereinto; an annular inlet valve encircling the piston rod and commanding 15 one of said inlet ports; said valve when open, serving as a baffle to spread the motive fluid on its way into the cylinder.
- 15 3. In an internal combustion engine, the combination of a power cylinder having a piston and a piston rod; a combustion chamber; a motive fluid inlet port opening directly thereinto; an annular inlet valve commanding the inlet port; said valve loosely encircling the piston rod but held 20 spaced from and out of direct contact therewith.
- 25 4. In an internal combustion engine, the combination of a power cylinder having a piston and a piston rod; a combustion chamber; a motive fluid inlet port opening directly thereinto; an annular valve commanding the inlet port; said valve having a tubular stem through which the piston rod passes; said stem being held spaced from 30 and out of contact with the rod; and a gear mechanism for operating the valve through the medium of said tubular stem.
- 35 5. In an internal combustion engine, the combination of a power cylinder having a piston and a piston rod; a combustion chamber; a motive fluid inlet port opening directly thereinto; an annular inlet valve surrounding the piston rod and commanding the inlet port; a valve housing having a passage therethrough communicating with the inlet port; means discharging the motive fluid laterally into the housing passage; and means in the housing causing the flow of 40 said fluid to be turned in the direction of the longitudinal cylinder axis before reaching the inlet port, for the purpose set forth.
- 45 6. In an internal combustion engine, the combination of a power cylinder having a piston and a piston rod; a combustion chamber; a motive fluid inlet port opening directly thereinto; a valve housing surrounding the piston rod and having a passage therethrough communicating with the inlet port; an annular valve encircling the 50 piston rod and commanding the inlet port;
- 55 a conduit discharging into the valve housing passage; a control means at the receiving end of said conduit for measuring, and letting forward into the power cylinder alternate bodies of scavenging air and of combustible mixture.
- 60 7. In an internal combustion engine, the combination of a power cylinder having a piston and a piston rod; a combustion chamber; a motive fluid inlet port opening directly thereinto; a valve housing surrounding the piston rod and having a passage therethrough communicating with the inlet port; an annular inlet valve encircling the piston rod and commanding the inlet port; a conduit discharging into the valve housing passage; said conduit projecting laterally from the valve housing and passing through the housing part of the engine frame; and means supplying motive fluid to said conduit.
- 65 8. In an internal combustion engine, the combination of a power cylinder having a combustion chamber; a motive fluid inlet port opening directly thereinto; a valve housing comprising an outer and an inner tubular part spaced from each other and communicating with the inlet port; a piston and a piston rod; the rod passing through the inner tubular part of the housing; and an annular inlet valve encircling the piston 70 rod and commanding the inlet port.
- 70 9. In an internal combustion engine, the combination of a power cylinder having a piston and a piston rod; a combustion chamber; a motive fluid inlet port opening directly thereinto; a valve housing inclosing a portion of the piston and having a passage therethrough communicating with the inlet port; an annular puppet valve encircling the piston rod and commanding the inlet 75 port; said valve having an integral tubular stem held spaced from and out of contact with the piston rod, said stem being sustained by and slidably mounted in the housing parts; and a packing between the tubular stem and the housing parts.
- 75 10. In an internal combustion engine, the combination of a power cylinder having a piston and a piston rod; a combustion chamber; a motive inlet port opening directly thereinto; an annular inlet valve encircling the piston rod and commanding the inlet port; a cylinder head comprising a gyrate head wall also encircling the piston rod, whereby the valve when open co-acts 80 with the surrounding gyrate head wall to spread the motive fluid on its way into the cylinder.
- 80 11. In an internal combustion engine, the combination of a power cylinder having a piston and a piston rod; a combustion chamber; an inlet port opening directly thereinto; a cylinder head comprising a gyrate head wall encircling the piston rod, one end 85 of which wall is attached to the cylinder 85

- end; and an inlet valve also encircling the piston rod and commanding the central inlet port opening in the other end of said head wall.
12. In an internal combustion engine, the combination of a power cylinder having a piston and a piston rod; a cylinder head comprising a gyrate head wall positioned about the longitudinal cylinder axis, one end of which wall is attached to the cylinder end; an inlet valve commanding the central inlet port opening into the other end; a jacket wall inclosing but spaced from the head wall to form a cooling chamber; and means relieving the expansion stress of the head wall with respect to its jacket wall.
13. In an internal combustion engine, the combination of a power cylinder having a piston and a piston rod; a combustion chamber; a motive fluid inlet port opening directly therewith; a cylinder head comprising a gyrate head wall; said wall having flanged ends, one of which is attached to the cylinder; a detachable valve housing fastened to the other flange, said housing having a motive fluid passage therethrough communicating with the inlet port; and an inlet valve encircling the piston rod and commanding the inlet port.
14. In an internal combustion engine, the combination of a power cylinder having a piston and a piston rod; a combustion chamber; a motive fluid inlet port, opening directly therewith; a cylinder head comprising a gyrate head wall encircling the piston rod, one end of which is attached to the cylinder; a valve housing fastened to the other end of the head; a motive fluid passage through said valve housing communicating with the inlet port; an inlet valve commanding the inlet port and encircling the piston rod but held spaced therefrom and out of contact therewith; and a gear mechanism for positively operating the valve.

In testimony whereof we have signed our names to this specification in the presence of two subscribing witnesses.
